UNITED STATES PATENT OFFICE.

CHARLES STOLL, OF CHICAGO, ILLINOIS.

FIRE-ESCAPE.

SPECIFICATION forming part of Letters Patent No. 662,036, dated November 20, 1900.

Application filed September 18, 1900. Serial No. 30,397. (No model.)

To all whom it may concern:

Be it known that I, CHARLES STOLL, a citizen of the United States, residing at Chicago, in the county of Cook and State of Illinois, 5 have invented certain new and useful Improvements in Fire-Escapes; and I do declare the following to be a full, clear, and exact description of the invention, such as will enable others skilled in the art to which it appertains 10 to make and use the same, reference being had to the accompanying drawings, and to the letters of reference marked thereon, which form a part of this specification.

This invention relates to an improvement 15 in fire-escapes, more especially a portable fire-escape, and is embodied in the novel parts, arrangement, and combinations of parts hereinafter described, and particularly set forth in the claims.

20 It is one object of the invention to produce a simplified, strong, and efficient construction for a portable fire-escape adapted to be secured to a suitable object in or about the room of a building—such, for instance, as the window-frame—and having a reel for paying off a suitable metallic tape, cable, or the like, and having suitable means within ready reach of the party using the escape by which the reel can be controlled and the rapidity of 25 descent governed to suit the party using the apparatus.

A further object is to provide suitable means, preferably in the form of a folding handle, for turning the reel to rewind the 30 tape or cable thereon.

35 A further object of the invention is to produce a fire-escape of exceedingly simple, cheap, durable, and effective construction.

In the accompanying drawings I have illustrated 40 a practical embodiment of the invention, but desire it understood that I do not wish the same to be limited in its useful application to the particular construction which for the sake of an understanding of the invention is therein illustrated.

45 In the drawings, Figure 1 is a side elevation of a fire-escape embodying my invention. Fig. 2 is an end elevation of the same, and Fig. 3 is an elevation showing the operating- 50 handle for the reel.

Referring to the drawings, A indicates a reel or spool, to which is attached one end of

the metallic tape, cable, or other suitable flexible member B, the tape or cable being wound about the reel and provided at its free 55 end with a hook C or other suitable device capable of being quickly and easily attached to a window-frame or other suitable part for supporting the apparatus and the person using the same for the purpose of descent. 60

D indicates a journal or axle fixed to the reel and extending through bearings E in arms F, depending at the sides of the reel from said journal or axle. One end of the journal D projects beyond one of the arms F 65 and has secured thereto a disk G of substantially the size circumferentially of the reel A. Pivoted to this disk is a handle g, adapted to be folded down against the disk side or to be turned up at right angles thereto to serve 70 as a crank-handle for operating the disk and reel for the rewinding of the tape or cable thereon.

H indicates a spring adapted to bear at one end against either of two shoulders h on the 75 handle, so as to hold the latter either flat against the disk or standing at right angles thereto. The spring is secured to the disk. Between and secured to the lower ends of the arm F is a handle J, suitably fashioned to form 80 a comfortable grip for the hand of the person. Secured to one end of the handle J and curved upwardly toward and secured at each side to the arms F is a finger or hand guard K, adapted to protect the hand of the user of the escape 85 from coming in contact with the cable or tape or the walls of the building or other objects while the escape is being used. The guard K at its upper end is preferably provided with upwardly-bent flanges k, lying beside the spool 90 or reel and secured to the arms F, as by means of screws k'. Between the arms F below the spool is pivoted at l a brake-shoe L, adapted to contact with the side flanges of the spool or reel. The shoe is also made sufficiently 95 wide at one side to frictionally engage the periphery of the disk G in order to gain additional frictional contact. The brake-shoe L is provided with a trigger or grip M, extending substantially parallel with the handle J 100 and between the same and the finger-guard. The grip is within easy reach of the fingers grasping the handle J. At its end the trigger M is bifurcated and extends at the side

beyond the guard K, the latter forming the guide and brace for the trigger. Secured to a cross piece or bar N at the end of the trigger is one end of a spring O, the other end of 5 which is secured to a suitable part, such as the finger-guard, the spring exerting a pull on the end of the trigger and causing the brake-shoe to frictionally engage the reel and disk. The spring is preferably adjustably 10 secured at one end to the finger-guard or other part, so as to give more or less tension on the trigger. Any suitable means may be employed for this purpose. In the drawings the end of the spring o is adapted to engage in 15 any one of a series of holes P in the finger-guard, and the spring is preferably provided with a loop or finger-hold, whereby it can be grasped and placed in any desired hole.

Q indicates a suitable belt or rope secured 20 at one end to a part of the escape, such as the handle. The rope is adapted to be passed about the body of the person using the escape and secured at its other end detachably to some part of the escape. For this purpose I 25 have shown the belt provided with a hook q, adapted to engage in the opening q' in the handle J.

It is believed the use and operation of the device will be manifest from the above description. A person desiring to use the escape passes the belt Q about his body and secures the end to the opening q'. He then attaches the hook C on the cable B to a window-frame or the like, grasps the handle J and the 35 trigger M, and is ready to lower himself, governing the speed of descent by the pressure brought to bear on the trigger M. If preferred, the spring O can be adjusted to exert sufficient tension on the brake-shoe, the cable A secured about the body of the user, and the escape attached in any suitable manner, as by means of a belt, to some suitable part 40 in or about the apartment. The user then swings himself from the window, the brake being held with sufficient pressure against 45 the reel to insure a slow descent.

Having thus described my invention, what I claim as new, and desire to secure by Letters Patent, is—

1. In a fire-escape, the combination of a reel, a flexible member secured thereto, a journal for said reel, arms depending from said journal, a brake pivoted between said arms and adapted to bear against said reel, a handle secured to the lower ends of said arms, 55 and an operating-trigger for said brake extending between said arms substantially parallel with said handle and between the same and said reel within reach of the fingers of the person using the fire-escape, substantially 60 as described.

2. In a fire-escape, the combination of a reel, a flexible member secured thereto, a journal secured thereto, arms depending from said journal, a disk secured to said journal, 65 a handle on said disk, a handle secured to the lower ends of said arms, a brake pivoted to said arms and adapted to engage both said reel and said disk, and an operating-trigger for said brake extending adjacent to said 70 handle, substantially as described.

3. In a fire-escape, the combination with a reel, a flexible member secured thereto, a journal for said reel, arms depending from said journal, a handle secured between the 75 lower ends of said arms and extending laterally therefrom, a finger-guard secured to the other end of said handle and also secured to said arms, a brake pivoted between said arms and adapted to engage said reel, a trigger for 80 said brake extending between said guard and said handle and being guided at its free end by said guard, and a spring secured to said trigger and to a suitable part of the fire-escape, substantially as described.

In testimony whereof I affix my signature in presence of two witnesses.

CHARLES STOLL.
